UNITED STATES PATENT OFFICE

THOMAS RANDOLPH HARRISON, OF PHILADELPHIA, PENNSYLVANIA, ASSIGNOR TO BROWN INSTRUMENT COMPANY, OF PHILADELPHIA, PENNSYLVANIA, A CORPORATION OF PENNSYLVANIA

AUTOMATIC CONTROL SWITCH APPARATUS

Application filed June 4, 1924. Serial No. 717,902.

The present invention relates to improvements in apparatus for automatic control systems.

More particularly the invention relates to apparatus for controlling recorders, switches, motors, valves, rheostats and like devices in response to mechanical, chemical, electrical or other physical conditions in order to effect a record of the changes, or to maintain predetermined conditions at controlled points.

10 The present invention comprises improvements in the apparatus disclosed in copending application, Serial Number 701,829, filed March 25, 1924, in which improved contacting galvanometer and control arrangements are disclosed. In the copending case the contacting galvanometer arrangements control a pair of light contacts, which in turn control a set of electromagnetic switches through re-laying circuit arrangements. The electromagnetic switches in turn, control reversing motors which may be utilized to operate scale weights and like devices for automatic control purposes.

25 An object of the present invention is the provision of contacting galvanometer arrangements in which the electromagnetic switches are eliminated and the control contacts are directly and mechanically controlled by the contacting galvanometer.

30 Another object of the invention is the provision of mechanically controlled contacts of rugged construction with which relatively heavy currents may be handled without sticking thereof, and without destructive arcing.

35 A further object of the invention is to provide simplified, more efficient and more reliable contacting galvanometer arrangements than have been heretofore available.

40 Other objects of the invention will appear in the following detailed description of preferred embodiments thereof, of which—

Fig. 1 is a perspective view showing a preferred form of the invention.

45 Fig. 2 is a side view showing a modification of the form shown in Fig. 1.

Fig. 3 is a perspective view showing another form of the invention.

50 Fig. 4 is a perspective view showing still another form.

Fig. 5 is a side view showing a modification of the form shown in Fig. 4.

Referring to Fig. 1, a shaft 1 is driven at a uniform rate by a suitable motor not shown, and has mounted thereon a cam 2. An actuating member 3, pivoted at 4 to a suitable fixed support 5 has secured thereto an actuating pin 6 which is normally forced against the surface of cam 2 by means of a spring 7 secured to and urging member 3 upward. Pivoted secured to the free end of member 3 by pin 8 is a pair of substantially vertical connecting links 9. At the upper ends of links 9, shoulders 10 are formed which are adapted to hook over projecting pins 11 which in turn are secured to frame 12. Frame 12 is pivotally supported at 13 from fixed support 14 and normally tends to move upward under influence of springs 15 until the forward upper edge engages fixed stop 16. The lower front edges 17 of frame 11 are formed in a shallow inverted V-shape. Pivoted secured to links 9 by spindle 18 is a member 19 which extends to the right in Fig. 1 and acts as a spacer between links 9. It will be noted that spindle 18 and the end of member 19, join links 9 together for movement about pin 8 as a pivot under influence of light springs 23. The free end of 19 rests on a surface 20 and is held against a shoulder 21 of a fixed stop 22 by the action of springs 23. Pivoted mounted on a spindle 24 supported from a fixed support 25 is a pair of contact carrying members 26 and 27 provided with extensions 28 and 29 which are positioned beneath and adapted to engage member 19.

55 Contact carrying members 26 and 27 are forced downward by relatively heavy flat springs 30 and 31 secured at one end thereto and secured at their other ends to fixed support 22. Secured near the outer ends of members 26 and 27 are latch projections 32 and 33 shouldered and positioned to be engaged by shoulders 34 and 35 of pivoted bell crank members 36 and 37. Members 36 and 37 are pivoted mounted on a fixed supporting spindle 38 and are normally urged towards a fixed stop 39 by springs 40 and 41. Secured to the bell cranks are actuating bars or extensions 42 and 43. Extensions 42 and 43 are 60 65 70 75 80 85 90 95 100

positioned immediately below the front part of frame 12, within the side members thereof, and extend towards the center of the frame with a space left between their inner ends. 5 A contacting galvanometer coil 44 is mounted for pivotal movement on supports 45 and has secured thereto a needle or pointer 46 which in normal or undeflected position of the galvanometer, extends immediately below the apex of the V-shaped notch formed by surfaces 17 in the front piece of frame 12, and immediately above the central space between the inner ends of extensions 42 and 43. The arrangement is such that when the galvanometer is deflected the needle 46 is positioned over one or the other of extensions 42 and 43.

Secured to members 26 and 27 are relatively large contacts 47 and 48, which coact 20 with adjustable contacts 49 and 50 mounted in fixed bar or support 51. Formed on links 9 are disengaging projections 52 and 53 so shaped and positioned that with the parts as shown in Fig. 1, the shoulders formed thereby will clear the ends of members 26 and 27 as links 9 move vertically under the influence of cam 2 and springs 7 and 15. When member 26 or 27 is released, to close the contacts controlled thereby, the arrangement is such that extension 28 or 29 will kick the end of 19 off shoulder 21, and springs 23 will then force members 9 to the right until projection 52 or 53 engages the end of the corresponding member 26 or 27. The free end of member 19 will rest on shoulder 54 of stop 22 in this position of parts, and the initial movement of the upper ends of links 9 will be sufficient to disengage shoulders 10 from pins 11. Frame 12 will then move upward under influence of springs 15 until it engages stop 16. As links 9 approach the bottom of their vertical movement, the shoulder formed by the projection 52 or 53 will slip under the end of the released one of members 26 or 27. Immediately thereafter pin 6 will drop off the shoulder on cam 2 under the influence of spring 7, and member 3 together with links 9 will move suddenly upward carrying the free end of the released member 26 or 27 upward and separating the contacts 47 and 49 or 48 and 50. As soon as frame 12 is released and moves upward the bell crank 36 or 37 which has been actuated will move into engagement with stop 39 under the influence of spring 40 or 41. On the upward movement of parts, the projection 32 or 33 will engage the end of the actuated bell crank and will cam the lower end thereof to the left against the tension of the spring 40 or 41 individual thereto.

As the shoulder 32 or 33 passes by shoulder 34 or 35 of bell crank 36 or 37, spring 40 or 41 will urge the lower end of the actuated bell crank to the right latching the actuated

member 26 or 27 in the position shown in Fig. 1.

After the actuated member 26 or 27 has been restored to latched position, movement of links 9 continues upward carrying the outer end of horizontally projecting spring 55 secured thereto into engagement with fixed member 56. This causes a flexing of spring 55 and tends to force links 9 to the left about pivot 8 against the tension of springs 23. The initial flexing of spring 55 will shift surfaces 57 of links 9 against pins 11, and as or just before the upward movement of links 9 is completed, shoulders 10 will slide over and engage pins 11, the end of member 19 will re-engage surface 21 of stop 22, and the parts will assume the position shown in Fig. 1.

In practice, the galvanometer 44 is connected by conductors 58 and 59 to a suitable control circuit, and contacts 47 to 50 are connected to circuits controlling suitable motors, rheostats, switches or like devices. In applying the arrangement to the recorder circuits as shown in the above mentioned copending application, the contacting galvanometer and electromagnetic switches there shown are removed, and leads 58 and 59 of the galvanometer coil 44 shown herein are connected directly to leads 60 and 62 of the copending case. With the switches of the copending case removed, contacts 49 and 50 of the present arrangement are connected to the line conductor L' and contacts 47 and 48 are connected to the conductors 58 and 59 of the copending case.

In operation, shaft 1 rotates continuously. Under the influence of cam and springs 7 and 15, links 9 and frame 12 are given a downward movement until pin 6 drops off the cam shoulder, and the springs 7 and 15 operate to throw the frame and links suddenly upward. So long as no deflection of the galvanometer needle occurs, members 26 and 27 will be latched in the position shown in Fig. 1, and member 19 will rock on stop 22 as links 9 move vertically, in this manner preventing movement of links 9 to the right about pin 8 under the influence of springs 23. In this manner shoulders 10 will be held hooked over pins 11 of frame 12. Under these conditions, pointer 46 will pass downward between the ends of extensions 42 and 43, as the frame lowers. Upon a deflection of the galvanometer needle, due to an unbalance caused by the conditions to be controlled or measured, pointer 46 will be positioned over one or the other of the extensions 42 or 43. As the frame is lowered, pointer 46 will rock downward and engage the extension 42 or 43 over which it is positioned and continued downward motion of frame will force the latching arm of the corresponding bell crank 36 or 37 to the left in Fig. 1, until the corresponding member 26 or 27 is freed to move under the

influence of its spring 30 or 31. The released member 26 or 27 will snap downward causing contact 47 or 48 to engage contact 49 or 50 as the case may be, with a blow which insures engagement of a substantial area of the contact surfaces and thereby avoids overheating and burning of the contacts due to imperfect engagement thereof. As the contacts are trip controlled, relatively heavy contacts and parts may be used so that large currents may be directly handled without the necessity of resorting to relay controlled switches. The movement of the released member 26 or 27 is such that the corresponding extension 28 or 29 will engage member 19 and kick the end thereof off shoulder 21 of stop 22. Links 9 will then move to the right under influence of springs 23 until projection 52 or 53 engages the tripped member 26 or 27. As above set forth, this movement of links 9 about pivot 8 will disengage shoulders 10 from pins 11, permitting frame 12 to move upward against stop 16. The upward movement of the frame immediately frees the galvanometer needle 46 so that a new position may be assumed thereby. Links 9 will continue to move downward until just before pin 6 drops off the cam shoulder at which point the shoulder formed by projection 52 or 53 will slip under the end of the tripped member 26 or 27. When pin 6 drops off the cam shoulder, spring 7 will snap links 9 and the actuated one of members 26 or 27 upward, causing a sudden disengagement of contacts 47 and 49 or 48 and 50, latching the actuated member 26 or 27 in the position shown in Fig. 1, and finally hooking shoulders 10 over pins 11 as above set forth. The sudden interruption of the contacts reduces sticking and arcing of the contacts. The contacts may be made of sufficient size to remain cool in operation so that any arc on interruption will be rapidly extinguished. Any common and well known expedient for preventing arcing, as for example a condenser connected across the contacts, may be utilized when highly inductive circuits are to be interrupted. With shoulders 10 hooked over pin 11, the cycle of operations is complete, and succeeding cycles may proceed.

Owing to the inclination of surfaces 17 of frame 12, it will be clear that the point in the downward movement of frame 12 at which the contacts will be tripped will vary with the degree of deflection of the pointer. As the point of interruption of the actuated contacts is definitely fixed in the cycle, the time interval during which the contacts will be closed varies directly with the degree of deflection. It will, however, be obvious that the same effect may be attained by making the lower front edge of frame 12 straight and inclining the upper edges of extensions 42 and 43 at suitable angles with relation to the frame.

The form shown in Fig. 1 is especially adapted for quick acting sensitive arrangements, because of the fact that the galvanometer needle is freed to assume a new position in accordance with changed conditions as soon as either contact is tripped. For slower acting arrangements where there is no need for freeing the needle or pointer 46 immediately, the mechanism may be simplified. Such an arrangement is shown in Fig. 2. This form is similar in structure to the form shown in Fig. 1, except for the following noted changes. Links 9 are permanently connected to pins 11 of frame 12, and springs 15, member 19, stop 22, extensions 28 and 29, spring 55 and stop 56 are eliminated. The ends of contact members 26 and 27 are extended to project into the path of vertical movement of projections 52 and 53 on links 9. The shape of cam 2 and the proportions of parts are such that the shoulders formed by projections 52 and 53 will drop sufficiently to permit engagement of contacts 47 and 49, and 48 and 50 before member 26 or 27 is tripped.

In operation, with the galvanometer undeflected, pointer 46 will pass between the ends of extensions 42 and 43, and contacts 48 and 49 will remain latched up. When a deflection occurs, the downward movement of links 9 will drop projections 52 and 53, then one or the other of the bell cranks 36 or 37 will be actuated to release the corresponding contact member 26 or 27. The contacts will remain closed and pointer 46 will be engaged by frame 12 until pin 6 drops off the shoulder of cam 2, when spring 7 will move the parts upward carrying with it the actuated contact member, and latching the contacts apart. The pointer 46 is then released and may assume a new position, and the cycle of operations may be repeated. A full understanding of this form will be had by referring to the disclosure set forth for Fig. 1.

A modified arrangement for accomplishing the functions and operations set forth in connection with Fig. 1 is shown in Fig. 3. Pivoted to supporting spindle 13 of frame 12 is an actuating structure comprised of links 60 and 61 which at their lower end have a toe 62 secured thereto. The end of toe 62 is held against cam 2 by means of spring 63. Frame 12 has extensions 64 and 65 formed integrally therewith which extend in forward and downward manner and have rigidly secured between the ends thereof an actuating extension 66. A spring 67 secured to extension 66 at one end and to a suitable fixed support at the other end urges the lower end of extension 66 into engagement with a shoulder 68 of member 69. Member 69 is pivotally connected by means of pin 70 to links 60 and 61. A flat spring 71, secured to an extension 72 of member 69 is adapted to engage extension 66 and will force member 68 into the

position shown in Fig. 3, when frame 12 is against stop 16 and toe 62 is against the low part of cam 2. Integrally formed with the free end of members 69 is an extension 73 which is positioned to be actuated by projection 74 or 75 of contact carrying bell cranks 76 and 77. Bell cranks 76 and 77 are pivotally mounted on a suitably supported spindle 78 and tend to move to the right under the influence of springs 79 and 80. Mounted respectively on bell cranks 76 and 77 are contacts 47 and 48, arranged to coact with contacts 49 and 50 mounted on block 51.

Contacts 47 to 50 are held in disengaged position by means of latch members 81 and 82 pivoted on fixed spindle 83 and the inner ends of which are held in engagement with shoulders 84 and 85 of bell cranks 76 and 77 by the action of springs 79, 80, 86 and 87. Mounted on the outer ends of latches 82 and 83 are trip bars 42 and 43, which as set forth in connection with Figs. 1 and 2, are positioned beneath and within the front end of frame 12, with their inner ends separated to permit downward movement of galvanometer pointer 46 in central or balanced position without engaging either as frame 12 rocks the pointer downward. Formed integrally with member 69 is a contact restoring extension 88 which is positioned and adapted to engage projections 89 and 90 of bell cranks 76 and 77, to interrupt the contacts 47 and 49, or 48 and 50, and to restore the actuated one of the bell cranks to latched position when toe 62 drops off the shoulder of cam 2 under influence of spring 63.

In operation of this form, a rocking motion is imparted by cam 2 and spring 63 to toe 62 which in turn produces an oscillating movement of member 69 about 13 as a pivot. Movement of 69 is imparted to member 66 by shoulder 68, and in this manner frame 12 is rocked vertically about pivot 13 against the tension of spring 67. So long as pointer 46 is undeflected, no other effect will be produced. When the galvanometer is deflected however, pointer 46 will be positioned over bar 42 or 43, and at a point in the descent of the frame depending upon the degree of deflection, member 80 or 81 as the case may be, will be actuated to disengage the end thereof from shoulder 84 or 85 of bell crank 76 or 77. The released bell crank will then snap forward under the influence of its spring 79 or 80 causing projection 74 or 75 to engage extension 73 of member 69, forcing it downward, and finally causing engagement of contacts 47 and 49, or 48 and 50 with an impact. The downward movement of member 69 removes shoulder 68 thereof from engagement with the end of member 66, and member 66 together with frame 12 engages stop 16. The upward movement of the frame frees pointer 46 so that a new deflected position may be immediately assumed thereby. The arrange-

ment of parts is such that with the set of contacts closed, projection 89 or 90 of the actuated bell crank 76 or 77 will be in the path of movement of extension 88 on member 69 when toe 62 drops off the shoulder of cam 2. When this occurs spring 63 will move the actuating frame together with member 69 suddenly to the right in Fig. 3. This movement of 69 will cause 88 to force the actuated bell crank 76 or 77 upward about pivot 78, causing a sudden interruption of the engaged contacts, and moving the upper arm of the actuated bell crank to the left until the end of latch 81 or 82 drops back of shoulder 84 or 85 under the influence of spring 86 or 87 and latches the bell cranks in unactuated position as shown in Fig. 3. After the latching is effected, due to the flexing of spring 71 in engagement with 66, surface 91 of member 69 will be forced into engagement with the end of member 66 until shoulder 68 slips over the edge of and re-engages the end of 66 at or just before the limit of movement of toe 62 to the right into engagement with the low point of cam 2. A suitable fixed stop 90' may be provided to limit the downward movement of member 69.

The application of this form to the recorder arrangement of the copending case is the same as set forth above for the connection of the form shown in Fig. 1, and the same functions and advantages are attained as are set forth in the description of Fig. 1.

In Fig. 4, a form of the invention is shown in which all of the contacts are movable. In this form, links 9 are permanently connected to pins 11 of frame 12 and the frame is rocked about pivots 13 under the influence of cam 2 and spring 7. Downward movement of frame 12 with the galvanometer 44 deflected will cause pointer 46 to engage one or the other of members 42 or 43 and will rock latch 81 or 82 downward against the tension of spring 86 or 87. Downward movement of latch 81 or 82 will release member 92 or 93 permitting the released one of these members to snap to the left about fixed pivot 94 under influence of spring 95 or 96, bringing contact 47 or 48 into engagement with contact 49 or 50, as the case may be. Springs 95 and 96 are secured to fixed supports 97 and 98. Contacts 49 and 50 are mounted on a bar 99 supported from a bar 100 which in turn is pivotally mounted on spindle 94 and acts as a spacer between members 92 and 93. A spring 101 secured to fixed support 102, forces member 99 to the left into engagement with a cam 103 mounted on a shaft 104. Shaft 104 is driven at the same speed as shaft 1 and in definitely fixed relation with respect thereto by suitable drive connections, (not shown). Secured to cam 103 are projecting pins 105 and 106 which are positioned to engage surfaces 107 and 108 of members 92 and 93 when these members are tripped, and to restore

them to latched position for the succeeding cycle.

In operation, member 92 or 93 will be tripped at a point in the downward movement of frame 12 depending upon the degree of deflection of the galvanometer, and one or the other set of contacts 47 and 49, or 48 and 50 will close with a blow. The parts are positioned and proportioned so that the tripped contacts will remain in engagement until member 99 drops off the shoulder of cam 103. At this point the engaged contacts will move together to the left in Fig. 4 until surface 107 or 108 of the tripped member 92 or 93 engages pin 105 or 106 when the movement of bar 99 will continue until the low point of the cam is reached, and the movement of 92 or 93 will be arrested. This effects a sudden interruption of the engaged contacts. Further movement of pin 107 or 108 will then immediately cam the lower end of the tripped member 92 or 93 to the right and will shift the upper end thereof to the left until latch 81 or 82 drops behind the latching shoulder under influence of spring 86 or 87 and locks the contacts in open position. During the restoration of the contacts to latched position, cam 2 permits the upward movement of frame 12. The parts are then in position for a succeeding cycle of operations.

It will be noted that the galvanometer needle is not freed in Fig. 4 until the normal upward movement of frame 12 occurs. Freeing of the needle as soon as the contacts are tripped may be effected as shown in Fig. 5. The cam 2 and spring 7 are positioned on the bottom of member 3 so that the downward movement of frame 12 is spring actuated, and the upward movement thereof is cam actuated. Secured to frame 12 is a magnetizable cross-bar or armature 109 which is positioned to be attracted by energization of an electromagnet 110 secured to a suitable fixed support, not shown. Magnet 110 may be energized through circuit comprising conductor 111, a source of electrical energy 112, contact spring 113, contacts 114 and 115, and conductor 116. Contacts 114 and 115 are positioned so that when either member 92 or 93 is tripped and causes engagement of the contacts 47 and 49, or 48 and 50, an extension 117 provided on each member 92 and 93, will force contact 114 into engagement with 115. Magnet 110 will be energized, raising frame 12 upward into engagement with stop 16, and pointer 46 will be freed to assume a new position. Magnet 110 will remain energized until the tripped member 92 or 93 is restored by pin 105 or 106 as set forth in connection with Fig. 4, when extension 117 will move away from contact spring 113 and will permit contacts 114 and 115 to separate, effecting de-energization of magnet 110. In this manner as soon as one or the other of the sets of contacts is tripped, frame 12 will be raised to free the pointer.

When this form is used with the contacting galvanometer of the copending case, magnet 110 may be connected directly in the lead from contacts 47 and 48 to L_1 , as no current will flow in this lead until one or the other of contacts 49 or 50 is tripped, and the flow will cease as soon as the tripped contacts are separated, resulting in the de-energization of the magnet.

It will be apparent that many modifications of the forms disclosed may be made by those skilled in the art without departing from the spirit of the invention.

Accordingly, what is desired to be secured by Letters Patent and claimed as new is:

1. Automatic control apparatus comprising a galvanometer and pointer therefor, periodically operating means adapted to actuate said pointer when deflected from its normal position, a plurality of sets of contacts, actuating springs for causing engagement of said contacts, and solely mechanical means between said pointer and said contacts for controlling the engagement thereof.

2. Automatic control apparatus comprising a contacting galvanometer, mechanical operating means coacting with said galvanometer and a plurality of spring closed contacts mechanically controlled by the coaction of said galvanometer and said operating means.

3. Control apparatus comprising in combination, a pair of contacts, a latch for maintaining said contacts in disengaged position, a galvanometer pointer adapted to mechanically actuate said latch, and cyclically operating means for said galvanometer pointer.

4. Control apparatus comprising in combination, a plurality of pairs of contacts, solely mechanical means individual to each pair of contacts to maintain the same in separated position, a galvanometer, a pointer for said galvanometer adapted to directly actuate said mechanical means to permit engagement of said contacts, and cyclically operating means coacting with said pointer to effect actuation of said mechanical means to permit engagement of said contacts at different points in the cycle of operation of said operating means varying with the degree of deflection of said galvanometer.

5. Automatic control apparatus comprising a galvanometer, mechanical means controlled by said galvanometer for actuating a plurality of contacts variably in accordance with the deflection of said galvanometer, and solely mechanical means independent of said galvanometer for invariably restoring the actuated ones of said contacts.

6. Automatic control apparatus comprising a galvanometer, mechanical means operating in cycles and coacting with said galvanometer, means actuated at different points in the cycles of operation of said mechanical means

in a manner dependent upon the amount of deflection of said galvanometer, and solely mechanical means for restoring said actuated means at the same point in each cycle.

5 7. Control apparatus comprising a contacting galvanometer, periodically operating mechanical means coacting with said galvanometer, a plurality of contacts caused to move into engagement by the coaction of said galvanometer and said mechanical means, and spring actuated means for suddenly interrupting said engaged contacts.

10 8. The combination as set forth in claim 6 in which said last mentioned means comprises spring actuated means for effecting a quick restoring movement of said actuated means.

15 9. In combination, a set of contacts; means for latching said contacts in disengaged position; a galvanometer; cyclically operating means coacting with said galvanometer to trip said latching means and permit engagement of said contacts; and solely mechanical means for restoring said tripped contacts to latched position.

20 10. The combination as set forth in claim 9 in which said last mentioned means is operated to restore said contacts at a predetermined point in the cycle of operations of said operating means.

25 11. The combination as set forth in claim 9 in which said last mentioned means comprises a spring operative to suddenly disengage said tripped contacts at a predetermined point in the cycle of operations of said operating means.

30 12. The combination as set forth in claim 1 together with means for freeing said pointer immediately upon the engagement of said contacts.

35 13. In combination, a plurality of contact carrying members normally held in unactuated position; releasing means to permit movement of said members to actuated position; a galvanometer comprising a pointer adapted to engage said releasing means; and operating means for forcing said pointer into engagement with said releasing means; and means actuated by the movement of said members to actuated position to free said operating means from engagement with said galvanometer needle.

40 14. The combination as set forth in claim 13 in which said last mentioned means is solely and entirely mechanical.

45 15. In combination, a galvanometer; a pointer for said galvanometer; actuating means for said pointer; operating means of said actuating means; releasable connection between said operating means and said actuating means; a controlling trip for said releasable connection; releasing trips actuated by said pointer; and spring actuated members controlled by said releasing trips; said spring actuated members being operative to actuate

said controlling trip to effect disengagement of said actuating means and said pointer.

50 16. Control apparatus comprising a pair of contacts, a galvanometer, a source of stored energy, periodically operating means controlled by said galvanometer for releasing said energy to operate said contacts and means for periodically storing said energy.

70 17. Control apparatus comprising a pair of contacts, a galvanometer, means controlled by said galvanometer for closing said contacts with a snap action and means for thereafter opening said contacts with a snap action.

80 18. Control apparatus comprising a contact member, a second contact member normally latched in disengaged position from said first contact member, a galvanometer, means controlled by said galvanometer for releasing said latched member to permit it to engage said first contact with an impact and means operative thereafter for breaking said contact and again latching said member with a snap action.

85 19. Control apparatus comprising a pair of contacts, a latch device for normally maintaining said contacts in disengaged position and a second device periodically operative to move said contacts to latch in disengaged position, said devices normally being ineffective.

90 20. Control apparatus comprising a pair of contacts, a latch device for normally maintaining said contacts in disengaged position, a galvanometer and periodically operating means co-operating with said galvanometer for operating said latch device to release said contacts to engagement.

95 21. Control apparatus comprising a pair of contacts, a latch device for maintaining said contacts in disengagement, means for periodically operating said device to release one of said contacts to engage the other contact, and a second device for operating said one contact to engage with said latch device operated by said first mentioned means.

100 22. Control apparatus comprising a pair of contacts, a latch device for maintaining said contacts in disengagement, means responsive to a predetermined condition in operating said device to release one of said contacts to engage the other contact, a second device for operating said contact to engage said latch device periodically controlled by said first mentioned means, said first and second device being normally ineffective to perform any operation during said periodic condition.

115 23. Control apparatus comprising a pair of contacts, a spring forcing said contacts to engage a latch device for maintaining said contacts in disengagement, periodically operating means, and a galvanometer including a deflecting member cooperating when in deflected position with said periodic means during its periodic operation for operating said

latch device to release said contacts whereby said contacts engage with each other.

24. Control apparatus comprising a pair of members normally latched in disengaged position, means periodically conditioned for releasing said members to permit them to move into engagement, said means being operative to periodically latch the unlatched members back into disengaged position.

10 25. Control apparatus comprising a plurality of members, latch devices for maintaining said members in disengaged position, means periodically conditioned for operating said latch device and a galvanometer co-acting with said last mentioned means for operating said latch device to release said members.

20 26. Control apparatus comprising a plurality of members normally latched in disengagement, periodically operating means for releasing said members from latched position, said means being normally ineffective and means operative following the release of said members to operate said member into latched

25 engagement.

27. Control apparatus comprising a member, a latch device for maintaining said member in latched position, means for operating said latch device for releasing said member, second means for operating said first mentioned means, said second means being also operative to operate said member to latched position.

28. Control apparatus comprising a pair of contacts, a galvanometer, means responsive to the movement of said galvanometer for closing said contacts with a snap action, and means operative following the closing of said contacts for releasing said galvanometer.

35 29. Control apparatus comprising a pair of contacts, means for normally latching said contacts in disengaged position, a galvanometer, a periodically operating member engaging said galvanometer for operating said latch member to release said contacts for engagement, and means operative upon the closing of said contacts for disengaging said periodically operating means from said galvanometer.

40 30. Control apparatus comprising a pair of contacts, a latch device for maintaining said contacts in disengaged position, a galvanometer, a member periodically engaging said galvanometer for operating said latch device to release said contacts, said periodically operating member being so positioned as to engage said galvanometer at various positions of its movement in accordance with the angular swing of said galvanometer.

45 31. Control apparatus comprising a pair of contacts, a galvanometer, a pointer, a periodic member, means controlled by said pointer and operated by said periodic member for conditioning said contacts for engage-

ment and means for operating said conditioned contacts into engagement with a snap action.

In testimony whereof, I affix my signature.
